(57) **CLAIM**

The ornamental design for a handle, as shown and described.

DESCRIPTION

FIG. 1 is a perspective view of the handle according to the invention;

FIG. 2 is a left side view of the handle;

FIG. 3 is a right side view of the handle;

FIG. 4 is a top view of the handle;

FIG. 5 is a bottom view of the handle;

FIG. 6 is a back view of the handle; and,

FIG. 7 is a front view of the handle.

The broken line showing of structure is for illustrative purposes only and forms no part of the claimed design.
